(57) **CLAIM**

The ornamental design for portion of a display screen with a graphical user interface, as shown and described.

DESCRIPTION

FIG. 1 is a front view of a user interface for a portion of a display screen showing the new design; and,

FIG. 2 is a front view of a user interface for a portion of a display screen showing the new design.

The broken line showings of the portion of the display screen, image, and the text ("IMAGE SEARCH", "suv", and "Search") form no part of the claimed design. The solid black shading represents a contrast in appearance.
